US00D669232S

(12) **United States Design Patent**
Chung et al.

(10) **Patent No.:** US D669,232 S
(45) **Date of Patent:** ** Oct. 16, 2012

(54) **BARK COLLAR HOUSING**

(75) Inventors: **Kim Wah Chung**, Shatin (HK);
Channing Miller, Fort Lauderdale, FL (US); **Michael Scalpato**, Boca Raton, FL (US); **Wing-Hung Tang**, Tsuen Wan (HK)

(73) Assignee: **Sunbeam Products, Inc.**, Boca Raton, FL (US)

(**) Term: **14 Years**

(21) Appl. No.: **29/408,473**

(22) Filed: **Dec. 13, 2011**

(51) LOC (9) Cl. **30-04**

(52) U.S. Cl. **D30/152**; D30/199; D30/155

(58) **Field of Classification Search** ..... D30/151–155, D30/144; 119/850, 855–860, 862–865, 654, 119/712–721, 725, 760, 762–776, 791–794, 119/815, 821, 724, 655, 51.02, 660, 174, 119/907, 908, 905; 24/16 R, 17 AP, 3.5 P, 24/188, 662, 324, 3.6, 307, 625, 616, 200, 24/196, 171, 169, 112, 614, 615, 115 F, 620, 24/681, 602, 306, 442, 274 R, 302, 300, 301, 24/298, 323, 16 PB, 265 H; D11/3, 12, 200, D11/7, 79–87, 97, 99, 107, 108, 137, 105, D11/103, 1, 2, 40–44, 46–49, 53, 56, 57, D11/59–61, 63, 65, 89, 90–92, 101, 106, D11/114–116, 201, 208–210, 212–218, 220, D11/230–234, 236, 237, 94, 6, 11, 93; D2/609, D2/627, 624, 632, 635, 976, 629, 631, 636, D2/614, 610, 639; 2/300, 311–319, 321, 2/322, 338, 339, 237, 170, DIG. 11, 365, 2/307, 308, 910, 917; D24/195, 211, 189, D24/190, 192; D3/207–212, 270–271.3, D3/327; D26/38; 206/37.1, 38.1; D6/302–304; 70/456 R, 456 B, 458, 459, 18, 49, 58; D8/1, D8/34, 38, 18, 394, 382, 396; 54/19.1; 63/1.11, 63/3.1, 3.2, 3, 9, 37, 38, 18–20, 23, 12, 13, 63/14.1, 21, 31, 15.2, 15, 1.13, 5.1, 1.1, 501,

63/22; 59/85, 89, 80, 81, 82, 79.3; 424/409; 43/131; 446/314, 376; 428/28; 606/203, 606/204, 201; 602/62; 128/876, DIG. 15; 40/633; 473/212, 216; 604/20; 231/7; 361/232; 403/212, 213, 391; 256/57, 47; 410/97, 410/23, 7; 292/307 R; 340/573.3; D10/104.1

(57) **CLAIM**

We claim the ornamental design for a bark collar housing, as shown and described.

DESCRIPTION

FIG. 1 is a front left perspective view of a bark collar housing showing our new design;

FIG. 2 is front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line portions are not claimed.
